PULSE CIRCUITRY STABILIZATION

Albert A. Auerbach, New York, N.Y., assignor to the United States of America as represented by the Secretary of the Air Force

Application July 23, 1957, Serial No. 673,749

6 Claims. (Cl. 178—71)

This invention relates to pulse circuitry, and particularly to the preselection and stabilization of the direct current operating level of an electron discharge device, to impart to such a device a constant operating level regardless of variations in the excitation currents associated therewith.

In a television system, particularly at the transmitter, there are present control voltages including video and synchronizing impulses of large magnitudes. These are to be impressed upon the control elements such as the grids of electron discharge devices. Usually these grids are biased at a preselected direct current operating level in order to obtain the requisite signals for transmission of images to television receivers. Video impulses impressed upon the grid of an electron discharge device, such as a modulator tube, may drive the grid positive into the grid current region and periodic negative synchronizing impulse may drive the electron discharge device to cut-off. The aforesaid impulses thus applied to the electron discharge device will tend to vary the pre-selected direct current operating level established at the control element, namely, the grid. This variation will be reflected in the output of the electron discharge device and will not be representative of the input control signals such as video and synchronizing impulses.

Accordingly, it is an object of this invention to provide new and improved apparatus for establishing a bias voltage at an electron discharge device at a preselected direct current level.

Another object of this invention is to provide new and improved apparatus for automatically stabilizing the aforesaid bias voltage at the preselected direct current level.

A further object of this invention is to clamp the bias voltage on an electron discharge device to a preselected direct current level, and from this level video voltage may drive the grid positive into the grid current region and periodic negative synchronizing impulses may drive the electron discharge device to cut-off, without affecting the said preselected direct current level.

In a preferred embodiment of this invention, a diode is connected to the grid of a television transmitter modulator tube. The said diode is biased to the sum of the preselected direct current level plus the required voltage of the periodic negative synchronizing impulse. When grid current raises the modulator tube bias, the diode passes and rectifies the peaks of the synchronizing pulse. The resultant direct current is applied to the grid of a control tube, whose plate voltage changes to effect a correction of the modulator tube bias.

For a better understanding of my invention, together with other and further objects, advantages and capabilities thereof reference is made to the following description and appended claims in connection with the accompanying drawings in which:

Fig. 1 is a schematic diagram of a specific embodiment of a bias stabilizer circuit for a television transmitter modulator tube;

Fig. 2 shows a curve for grid current against grid voltage of the television transmitter modulator tube;

Fig. 3 shows an equivalent circuit for the charging action for input signal coupling capacitor to the transmitter modulator tube in the bias stabilizer circuit shown in Fig. 1;

Fig. 4 shows a curve of the variation in grid bias voltage of the television transmitter modulator tube against time;

10 Fig. 5 is a curve showing the voltage depression characteristics of the modulator tube shown in Fig. 1; and

Fig. 6 shows a circuit for the charging resistance of stabilizer circuit shown in Fig. 1.

Now referring to Fig. 1, the television transmitter modulator tubes 2 and 3 in parallel are grid modulated by input video and synchronizing impulses impressed upon input terminals 40, and then coupled to said tubes by way of capacitor 32. These impulses are comprised of video impulses of amplitude E_v and periodic two microsecond negative synchronized impulses of amplitudes E_s and repetition rate of 16.2 kilocycles as shown at 1. The preselected direct current level on the parallel control grids 2—11 of parallel television transmitter modulator tubes 2 and 3 is $-E_g$, this level is established by 25 adjusting the plate load resistor 30 of control tube 5 (such as a 6Y6). Control tube 5 having two control grids 21—23, anode 5, and cathode 24. Adjustable load resistor 30 controls the initial plate to cathode voltage characteristic of tube 5 and thereby establishes a pre-selected voltage upon control grids 2—11 of modulator tubes 2 and 3 by way of resistor 19.

Diode 4 is biased to a magnitude of $-(E_g + E_s)$. Thus the negative peaks of synchronizing impulses E_s do not cause current flow through diode 4. Between 35 synchronizing impulses, cathode 7 of diode 4 is at $+E_s$ with respect to plate 8 of diode 4, so that no current can pass through the said diode in that interval. Negligible current flows through resistor 25, which placed cathode 24 of tube 5 at the plate potential of diode 4, 40 i.e. $(E_g + E_s)$.

A fixed grid current I_{go} (which is a function of $-E_g$ and R.F. excitation of modulator tubes 2 and 3 coupled into cathode line 16 by way of R.F. input terminals 17 and inductance loop 18) flows through resistor 19 as shown. The potential drop across control tube 5 is $+E_p$ (i.e. the plate potential with respect to cathode 24) the D.C. relations thus are expressed by equation:

$$(1) \quad E_p - I_{go}R_{19} - E_s = 0$$

50 The plate potential E_p is set by means of adjusting potentiometer 30 which is part of a voltage dividing network comprised of potentiometer 30 and resistor 31. The cathode potential of tube 5 is adjusted by means of potentiometer 26 which is a part of voltage dividing network comprised of potentiometer 26 and resistor 27. The cathode potential of tube 5 is designated as E_B , then $E_B = E_s + E_g$ and is set by bias level control potentiometer 30.

Positive video signal E_v applied to parallel grids 10—60 11 of modulator tube 2—3 respectively may vary in width. Considering the video as a single pulse, Δt may vary from 0 to possibly 11 microseconds with a corresponding variation in duty cycle 0 to 16%.

65 Referring to Fig. 2, where i_g (grid current) is plotted against e_g (grid voltage) it may be seen that considerably more than 4 milliamperes' grid current will flow during the video pulse interval (4 ma. being the normal grid current flow). An average grid current thus tends to flow depending upon E_v and the video duty cycle. Since 70 i_g flows so as to lower e_g , the modulator tube bias tends to depress at a rate determined by $T_{C_{32}}$, the charging time constant for coupling capacitor 32. The equivalent

circuit which indicates the charging action is shown in Fig. 3. R_g , the grid resistance of parallel modulator tubes 2 and 3, is included since the said tubes necessarily pass the charging or grid current. Since R_g is on the order of 1000 ohms, and resistor 19 is 4000 ohms, it determines R'_1 , the equivalent resistance primarily, thus $T_{C_{32}} = C_{32}R_{19}$.

Note from Fig. 1 that resistors 30 and 31 are paralleled by capacitor 33 which is on the order of capacitor 32. It will be seen the plate voltage E_p of tube 5 tends to rise when i_g increases, thereby reducing i_{gav} (the average grid current). We may then assume the i_g changes from I_{go} by a value equal to Δi_g , so that there tends to be a corresponding change in e_g equal to $e_g = R_{19}\Delta i_g$. The effect of capacitor 32 and equivalent resistor R'_1 , however, is such as to permit only an exponential rise in the bias of modulator tubes 2 and 3. This effect is summarized by the equation:

$$(2) \quad e_g = -E_g - \Delta e_g (1 - e^{-t/T_{C_{32}}})$$

where $\Delta e_g = (\Delta i_g)R_{19}$, and where $-E_g$ is the bias voltage desired, and is assumed to exist at $t=0$, at which time i_g changes by Δi_g . The value e_g thus tends to follow a curve such as is shown in Fig. 4.

The curve as shown in Fig. 4 should be modified to indicate the discharging time of coupling capacitor 32 between video pulses. This discharging action is controlled by the time constant TD_1 where TD_1 equals the product of capacitor 32 and the effective resistance of the network shown in Fig. 3 minus R_g .

$T_{C_{32}} = C_{32}R_g$ and $TD_1 = C_{32}R''_1$, R''_1 being the aforesaid effective resistance minus R_g . Resistor 19 alone however is on the order of four times as great as R_g , in addition to which we have an additional set of resistive elements in series. Thus $TD_1 = 10T_{C_{32}}$ so that the curve shown in Fig. 4 is not seriously modified by consideration of the discharging action.

As e_g depresses, the video and synchronizing impulses E_v and E_s respectively modulate grids 10-11 of modulator tubes 2 and 3 respectively, upward and downward from the new e_g level existing at the time t . This is shown in Fig. 5. This effect is of course exaggerated. In actuality, the effect would become useable only after a considerable number of cycles. Note that the synchronizing impulses E_s are correspondingly depressed as e_g becomes more negative.

Since diode 4 has been biased only by E_s , as soon as e_g depresses, diode 4 will pass current on the negative peaks of synchronizing voltage. This current must flow through resistor 25 charging capacitor 34 as shown in current flow path in Fig. 1. Thus grid 23 of tube 5 assumes a potential that is negative with respect to its cathode 24. This potential, which we may call $\Delta e'$, is clearly dependent upon e_g , diode 4 plate characteristic, and diode 4 rectifying load, i.e. resistor 25 and capacitor 34. Normally, $\Delta e' = 0$, since i_2 , the current through resistor 25 and diode 4, is negligible. The current through diode 4 will be of a pulsating nature, since it occurs only during the negative synchronizing peaks. It is clear that $\Delta e'$ can, at best, grow exponentially at a rate determined by $T_{C_{34}} = R_D + R_{19} + R_{30+31}(R'_2 C_{32} = T_{C_{32}})$, where R'_2 is the sum of R_D , resistance of diode 4, resistor 30, resistor 31, and resistor 19 as shown in the circuit for current flow through diode 4 in Fig. 6. R'_2 is the effective resistance seen from point G. the growth of $\Delta e'$ is modified by the factors mentioned above. Thus we have

$$\Delta e' = F(e_g, R_D, R'_2) e^{-t/R'_2 C_{32}}$$

where $\Delta e_g = (\Delta i_g)R_{19}$, and where $-E_g$ is the bias voltage resistance. R_g of tubes 2 and 3 in Fig. 1 is not in the circuit of Fig. 6, since i_2 flows at times that modulator tubes 2 and 3 are cut off.

Since $(R_D + R_{19} + R_{30} + R_{31})$ is less than R_{25} , R'_2 is on the order of simply these four resistances. Capacitor 34 is made small, so that $T_{C_{34}}$ is also small. This condition

is preferable if $\Delta e'$ is to grow rapidly, as will be seen, $\Delta e'$ is a control voltage which effects the bias stabilization of modulator tubes 2 and 3. The more rapidly $\Delta e'$ is built up, the more rapid is the bias stabilizing action. Thus, we maintain the relation: $T_{C_{34}}$ is less than $T_{C_{32}}$.

At this point consider T_{D_2} , the discharge constant for the circuit of Fig. 6 during the discharge interval, R_D is out of the circuit, since diode 4 is biased beyond cut-off. Thus, $T_{D_2} = C_{34}R_{25}$ and $T_{C_{34}} = C_{34}R'_2$.

However, R_{25} is less than R'_2 , so that the discharge of capacitor 34 proceeds much less rapidly than its charging, thus T_{D_2} is less than $T_{C_{34}}$ and this condition likewise is favorable for rapid compensation action.

Having examined the circuit action to the point of noting the creation of a voltage $\Delta e'$ when a change in e_g occurs, the bias stabilization effect can be considered. $\Delta e'$ is a negative voltage. Its effect is therefore to reduce the current through tube 5. The voltage e_p (which has been set at $e_p = E_p$) consequently increases but again its growth is exponentially limited by capacitor 33 across the plate load resistors 30 and 31 of Fig. 1. This, however, is desirable, since e_g has been exponentially decreasing. In fact, it is desirable to have $T_{C_{33}} = R'_3 = T_{C_{32}}$. Thus, the rate at which e_g depresses is the same rate at which e_p rises. R'_3 is the charging resistance for capacitor 33, the equivalent circuit being obvious from Fig. 1.

The effect of e_p rising is to oppose the decreasing e_g and provide a compensating voltage on plate 22 of tube 5. The magnitude of the change in e_p is such as to provide an equal (and opposite) change to e_g at grids 10 and 11 of modulation tubes 2 and 3 respectively. We thereby provide a complete grid voltage, i.e., bias stabilization at the grid of modulator tubes 2 and 3.

What is claimed is:

35. Apparatus to establish and automatically maintain a preselected D.C. voltage level at the control grid of a first discharge device drawing grid current comprising means to feed a signal consisting of positive and negative impulses by way of a capacitor to said control grid electrode, a second electron discharge device having grid, anode and cathode electrodes operating to establish said D.C. voltage level, said anode electrode of said second device being connected to said control grid of said first device by way of a resistor, a single diode serving to maintain said D.C. voltage level, having anode and cathode electrodes and only being responsive to said positive and negative impulses applied to said cathode electrode of said diode, said diode interconnecting said first device and said second device, a variable voltage source connected to said cathode electrode of said second device, and means for controlling the gain of said second device.

55. Apparatus to establish and automatically maintain a preselected D.C. voltage as defined in claim 1 including a first capacitor connected from said anode of said diode to ground and a second capacitor in parallel with said gain control means.

60. Apparatus to establish and automatically maintain a preselected D.C. voltage level at the control grid electrode of a first electron discharge device drawing grid current comprising means to feed a signal consisting of video and synchronizing impulses by way of a capacitor to said control grid electrode, a second electron discharge device operating to establish said D.C. voltage level and having grid, anode and cathode electrodes, said anode of said second device being connected to said control grid electrode of said first device by way of a resistor, said cathode electrode of said second device being connected to a variable voltage source and simultaneously by way of a resistor to said grid electrode of said second device, a third electron discharge device serving to automatically maintain said D.C. voltage level and having anode and cathode electrodes, said cathode electrode of said third device being connected to said control grid of said first device, said anode electrode of said third

device being connected to said grid electrode of said second device, and a variable resistor connected between ground and said anode electrode of said second device.

4. Apparatus to establish and maintain a preselected D.C. voltage level as defined in claim 3 also including a first capacitor connected from said anode electrode of said third electron discharge device to ground and a second capacitor in parallel with said variable resistor.

5. Apparatus to establish and automatically maintain a preselected D.C. voltage level at the control grid electrode of a first electron discharge device drawing grid current comprising means to feed a signal consisting of positive and negative impulses by way of a capacitor to said control grid electrode of said first electron discharge device, a second electron discharge device operating to establish said D.C. voltage level and having control grid, screen grid, anode and cathode electrodes, said anode electrode of said second device being connected to said control grid of said first electron discharge device by way of a resistor, said cathode electrode of said

second device being connected to a variable voltage source and simultaneously to said control grid electrode of said second device by way of a resistor, said screen grid electrode being connected to a fixed voltage source, a variable resistor connected from said anode electrode of said second device to ground, and a single diode serving to maintain said D.C. voltage level and having anode and cathode electrodes, said cathode electrode being connected to said control grid of said first device, said anode electrode being connected to said control grid of said second device.

6. Apparatus to establish and automatically maintain a preselected D.C. voltage level as defined in claim 5 also including a first capacitor connected from said anode electrode of said diode to ground and a second capacitor in parallel with said variable resistor.
